Primary Examiner — Karen S Acker*Assistant Examiner* — Jonathan E Fiencke(74) *Attorney, Agent, or Firm* — Birch, Stewart, Kolasch & Birch, LLP(57) **CLAIM**

The ornamental design for an air circulator, as shown and described.

DESCRIPTION

FIG. 1 is a perspective view of an air circulator showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing the air circulator in a state of use.

The evenly spaced broken lines and unshaded areas depict portions of the air circulator that form no part of the claimed design.

1 Claim, 8 Drawing Sheets(56)
